CLAMP OR HOOK FOR PRINTING PLATES

Albert J. Hoerth, Chicago, Ill., assignor to A. J. Hoerth and Company, Chicago, Ill., a corporation of Illinois

Application October 15, 1934, Serial No. 748,300

5 Claims. (Cl. 101—388)

This invention relates to clamps or hooks for printing plates and particularly to such clamps or hooks which are used for securing printing plates upon base plates which are provided with slots.

In the printing art such base plates may be either flat or cylindrical and may be provided with parallel or helical slots. These slots are undercut. The clamps to which this invention relates can be movably located in the slots and are provided with means for abutting against printing plates to hold them firmly on the base plate. In the printing trade these clamps are usually called "hooks".

15 One of the objects of the invention is to provide an improved printing plate clamp.

A further object of the invention is to provide a printing plate clamp capable of internal adjustment whereby the plate-engaging means may 20 be removed and adjusted independently of the main body of the clamp.

25 Other objects, advantages and capabilities of the invention will readily appear from the following description of preferred embodiments thereof, taken in conjunction with the accompanying drawings, in which

30 Figure 1 is a front view of a base plate assembly showing the manner in which printing plates are mounted thereon by means of the clamps;

35 Fig. 2 is an enlarged sectional view of a plate clamp embodying the invention, shown in operative position within the slot of a base plate;

Fig. 3 is a transverse section taken on the line 3—3 of Fig. 2;

40 Fig. 4 is a plan view, on a smaller scale, of the clamp shown in Figs. 2 and 3;

Fig. 5 is a side elevational view of the clamp illustrated in Figs. 2, 3 and 4, on the same scale as that employed in Fig. 4, illustrating the manner in which the clamping member is adjusted;

Fig. 6 is a longitudinal sectional view similar to Fig. 2, showing a further embodiment of the invention;

Fig. 7 is a transverse sectional view of Fig. 6, taken on the line 7—7 of Fig. 6;

Fig. 8 is a plan view on a smaller scale, showing the clamp mounted in the base plate;

Fig. 9 is an elevational view of the clamp illustrated in Figs. 6, 7 and 8 and showing the manner in which the clamping member is adjusted.

Fig. 10 is a longitudinal sectional view, similar to Figs. 2 and 6, showing a further embodiment of the invention;

Fig. 11 is a transverse sectional view taken on the line 11—11 of Fig. 10;

Fig. 12 is a plan view on a smaller scale showing the clamp mounted in the base plate;

Fig. 13 is a sectional view through the base plate, taken on the line 13—13 of Fig. 10, showing the clamp in elevation, and

Fig. 14 is an elevational view of the clamp illustrated in Figs. 10 to 13, inclusive, on the same scale as that employed in Fig. 12, illustrating the manner in which the clamping member is adjusted.

Referring to Fig. 1 of the drawings, the reference numeral 10 indicates a base plate of known type which is provided with slots 11. These particular base plates are flat, but it will be understood that cylindrical base plates having helical slots of similar cross section are well known in the art. The clamps or hooks of the present invention are adapted for use with both types of base plates.

As shown in Fig. 3, the slot 11 of one well-known type of base plate is provided near the surface of the plate with overhanging lips 12. The bottom of the slot 11 is undercut for the reception of an insert strip 13 which is provided with upwardly directed rack teeth 14 adjacent each side of the slot. The plates 10 are usually made of aluminum and the strips 13 are usually steel. The clamp illustrated in Figs. 2 to 5 inclusive, is intended for use with such a plate. This clamp comprises a main body 15 and a carriage 16 slidably mounted therein for movement in the longitudinal direction of the slot.

The main body 15 is provided with a longitudinal recess 17 which opens to the top and one end of the body, and the carriage 16 is mounted within this recess. The side walls of the recess 17 have longitudinal grooves 18 cut therein for the reception of tongues 19 on the carriage 16. Adjacent the bottom of the recess 17 is located a threaded rod 20, one end of which is rigidly mounted in the main body 15, being secured thereto by means of a pin 21. The rod 20 is operatively engaged by a nut 22 which is rotatably mounted on a depending portion 23 of the carriage 16.

The nut 22 is provided at one end with a bevel gear 24. Its other end rigidly receives a collar 25 which secures the nut permanently upon the carriage 16. The bevel gear 24 meshes with a bevel gear 26 which is pressed upon the reduced end 27 of a hollow pin 28. The pin 28 extends through the body of the carriage 16 and is suitably shouldered so as to provide a mounting for the pin 28 and bevel gear 26, which provides for the free rotation thereof. The bevel gear 26 may

be permanently mounted on the pin 28 by spreading the lower reduced end of the pin. The opening in the pin 28 is suitably of square or other non-round cross-section so that it may be rotated by means of the crank 29 shown in Fig. 5, which crank comprises a rod 30 of similar cross-section. At its upper end the pin 28 is provided with an annular shoulder 31 which is received in an annular recess in the surface of a clamping plate 32 which clamping plate is freely rotatable on the pin 28. The clamping plate 32 is preferably undercut along one longitudinal edge, as shown at 33 in Fig. 3.

The main body 15 is provided with a horizontal slot 34 which receives a latch member 35. The slot 34 and latch member 35 are normally located below the level of the overhanging lips 12 so that by suitable manipulation the ends of the latch member 35 may be brought under these lips, as shown in Fig. 4, so as to maintain the clamp within the slot 11.

The latch member 35 is preferably rigidly mounted on a pin 36 which has a pressed fit in a central opening in the latch member 35. The pin 36 passes through an opening 37 which extends from the upper surface of the main body 15 into the slot 34. The pin 36 has a central opening 38 of square or non-round cross-section whereby the latch 35 may be actuated by a suitable tool. It is preferred that the opening in the hollow pin 28 and the opening 38 should be of the same cross-section so that a single crank 29 may be used for actuating the gears 22 and 26 and the latch member 35. At the lower end 35 of the main body 15, teeth 39 are cut, which teeth are adapted to register with the rack teeth 14 of the insert strip 13.

In use, the hook or clamp which has just been described is placed by hand in an appropriate position in one of the slots 11, that is, a position which brings the beveled edge 33 of the clamping plate 32 very close to the desired position of one of the printing plates 40 which are to be mounted on the base plates 10. If it is desired to move the clamp or hook bodily, this may easily be done by lifting it manually out of the slot 11 and moving it along the slot. When again set down in the slot, the teeth 39 of the clamp engage the rack teeth 14 of the insert strip 13. The latch member 35 is rotated into the position shown in dotted lines in Fig. 4, and the engagement of the latch member with the overhanging lips 12 secures the clamp against upward displacement from the slot 11.

In order to adjust the clamping plate 32 very accurately, the crank 29 is inserted in the opening of the pin 28 and it is rotated in the appropriate direction. This rotation causes corresponding rotations of the bevel gears 26 and 24 and the rotation of the nut 22. The rotation of the nut 22, which is in operative engagement with the stationary threaded bar 20, causes the carriage 16 to slide, one way or the other, upon the main body 15 of the clamp. It will readily be understood that very minute adjustments of the clamping plate 32 may be made in this manner and that thereby the position of the printing plate 40 upon the base plate 10 may be very accurately controlled. It may here be noted that a very high degree of accuracy is necessary in this relation, particularly in color work where impressions in several colors are made in succession. This adjustment of the clamping plate 32 enables the successive impressions to be brought into very perfect register. I find that a single

latch member 35 is adequate to maintain the clamp in the slot 30. This fact is due to the location of the clamping plate 32 remote from the latch member 35. The pressure exerted by the printing plate 40 against the clamping plate 32 and the adjacent parts of the clamp, causes one end of the clamp to be forced downwardly towards the rack teeth 14. Any tendency of the clamp to turn as a whole is effectively prevented by the single latch member 35.

The embodiment of the invention illustrated in Figs. 6 to 9 inclusive, is intended for use with a base plate 41 having a somewhat different type of slots 42. These slots are not provided with lips adjacent the surface of the base plate but they are grooved to receive insert strips 43 which are provided with rack teeth 44 which become located on the sides of the slots 42 and extend longitudinally thereof. This clamp comprises a main body 45 and a carriage 46 slidably mounted therein. In plan the main carriage is of substantial U-shape, comprising side members 47 and an end member 48. The side members 47 are connected rigidly together by means of pins 49 which rigidly mount to and between the side members 47, a longitudinal rack 50 which is adapted to cooperate with a helical gear 51, which will hereinafter be more fully described.

The carriage 46 rides in the recess 52 provided between the two side members 47 and is provided with tongues 53 which slide in grooves 54 located in these side members.

On the outer sides of the side members 47 are cut a series of teeth 55 which correspond to, and are adapted to engage, the teeth 44 of the insert strip 43 when the clamp is dropped into one of the slots 42. It will be seen that owing to the engagement of the teeth 55 and 44 the main body 45 of the clamp is held against movement in the slot and before it can be moved bodily to another position, the clamp must be elevated to bring the teeth 55 and 44 out of engagement.

The main body 45 is cut away at one end on the level of the lower face of the teeth 44, as shown at 56 in Fig. 6, to provide a suitable position for the mounting of a latching member 57. This latching member is rigidly mounted on the lower reduced end of a pin 58 which extends through a vertical opening 59 in the main body 45. The pin 58 is provided at its upper end with a flange 60 which is received in an annular recess in the top surface of the main body 45. The pin 58 is provided with square or other non-round opening 61 for the reception of a crank 62 whereby the latch member 57 may be rotated into and out of latching position. In latching position the ends of the latching member 57 are projected below the teeth 44 so as to engage these teeth and hold the clamp against upward movement.

It will be understood that in this modification a clamping plate 63, similar to the clamping plate 32 of the previously described modification, is employed and that this clamping plate is located in spaced relation with respect to the latching member 57. When the clamp is in use to hold a printing plate upon the base plate 41, the latching member 57 prevents upward movement of one end of the clamp and the printing plate forces the other end of the clamp downwardly into the base plate.

The carriage 46 comprises a body which is recessed as at 64, for the accommodation of the helical gear 51. This helical gear is rotatably mounted upon a shaft 65 which extends across the recess 64 and which may suitably have a

pressed fit in openings in portions of the carriage which form the sides of the recess 64. This helical gear is located so as operatively to engage the rack 50.

- 5 The helical gear 51 is operated by a worm 66 which is located in a bore 67 extending from the upper face of the carriage into the recess 64. The lower end of the worm is reduced and is provided with a bearing in an opening 68 in the carriage.
- 10 The worm 66 is held in position by means of pins 69 driven into the carriage 46 and passing through an annular groove on the surface of the worm. The upward end of the worm is provided with a flange which is located in the recess in the upper surface of the clamping plate 63. It will be understood that the clamping plate 63 is mounted for free rotation upon the upper part of the worm 66. The upper part of the worm 66 is provided with a square or non-round opening 70, which is preferably the same in cross-section as the opening 61, so that both may be actuated by the same crank 62.

The operation of this embodiment of the invention is substantially similar to that of the embodiment first described. In short, the clamp is inserted in the slot in the base plate at a suitable location and rough adjustment is provided by merely unlocking the latching member 57 and lifting the clamp by hand to disengage the teeth 44 and 55. After locating the clamp in the desired position, the latching member 57 is turned into the position shown in dotted lines in Fig. 8 so as to lock the clamp in that position. Fine adjustment of the clamping plate 63 is attained by actuation of the worm 66, which has the effect of operating the helical gear 51. The direct engagement of the helical gear 51 with the rack 50 causes the desired slight movement of the carriage 46 with respect to the main body 45.

40 The embodiment of the invention illustrated in Figs. 10 to 14 inclusive, comprises a main body 71 on which is slidably mounted a carriage 72. The main body is provided with teeth 73 on each side which are adapted to engage with the teeth of rack strips 74 which are inserted inside of the groove 75 of the base plate 76. The main body is provided with shoulders 77 on each side, which shoulders are adapted to rest upon the upper ends of the teeth of strips 74. It will thus be seen that once placed in position, the main body 71 is not movable in the slot 75, but must be lifted out of the slot in order to be moved to a different position therein. It must be understood that this embodiment of the invention is not limited to the main body 71 being provided with teeth on its sides. It will be obvious that this embodiment of the invention may be adapted for use with a slotted base plate of the type shown in Figs. 2 to 4 inclusive, the main body 71 being provided with teeth on its lower face so as to engage the upwardly directed teeth in the bottom of slots of bases of this type.

65 The main body 71 is provided with a central longitudinal rack 78 and is chambered thereabove, as indicated at 79, for the reception of the sliding carriage 72. The sliding carriage 72 is provided with guide elements 80 which project into grooves 81 formed in the sides of the main body, these grooves opening inwardly into the chamber 79. The sliding carriage 72 is slotted as shown at 82, to provide for the mounting on the carriage of a worm wheel 83. This worm wheel 83 is adapted to cooperate with the rack 78 so as to effect the movement of the carriage 72 relative to the main body 71.

The worm wheel 83 is adapted to be operated by a worm 84 mounted in the main carriage in a suitable manner, for example, in the same way as the worm 66 of the embodiment illustrated in Figs. 6 to 9, inclusive. The shaft of the worm 84 is provided with a non-round opening 85 whereby the worm may be actuated by a suitable crank 86 in the manner shown in Fig. 14.

A characteristic of this embodiment of the invention is that the clamping plate 87 is mounted on the carriage 71 at the end thereof which moves outwardly away from the main body 71 during normal operation. The clamping member 87 is held in position by means of a pin 88, which may also suitably rigidly carry a latching element 89. In this particular embodiment, the latching element 89 is adapted to be turned by the pin 88 so that it may extend underneath the teeth of the racks 74, in the manner shown in Fig. 11. It will readily be understood that this latching element 20 may be located at a higher level in order to co-operate with overhanging lips in the case of a base plate of the type shown in Figs. 2, 3 and 4. The pin 88 is, of course, provided with a non-round opening so that it may be actuated by a 25 suitable crank.

It will be noted with particular reference to Fig. 10, that in this embodiment of the invention the plate 40 does not overlie any part of the clamp or hook. This results from the fact that the 30 clamping plate 87 is mounted at the outward extremity of the carriage 71. The clamp can, therefore, be readily removed and replaced in a more suitable position. All that it is necessary to do is to manipulate the latching member 89 and lift 35 the whole clamp bodily upwards. This may readily be done by grasping the clamping plate 87 by the fingers. After the main body is located in a suitable position, the crank 86 is engaged in the opening 85 of the worm 84 and rotated so as to 40 bring the clamping plate 87 into firm engagement with the printing plate 40.

It is normally preferred to provide freedom of adjustment of the carriage upon the main body in both directions. To facilitate this aim I prefer to 45 provide marks 90 on the upper surface of the carriage and main body. When these marks are brought into register, the carriage is practically at the center of its range of movement. The operator may adjust the clamping members to bring 50 these lines into alignment, whereupon he can be sure of ability to move the carriage to a known extent in both directions.

A further feature of this embodiment is that the carriage is locked directly to the base plate. 55 It may here be noted that the latching member 89 is located below the clamping plate 87 and prevents the clamp as a whole from being moved upwardly at this end. The effect of the printing plate 40 against the clamping plate 87 is to force 60 the end of the clamp remote from the clamping plate, downwardly into the slot 75. It is not considered necessary, therefore, to provide a latching member at both ends of the clamp, but this may be done if desired. 65

Although the invention has been disclosed in connection with the specific details of preferred embodiments thereof, it must be understood that such details are not intended to be limitative of the invention except in so far as set forth in the 70 accompanying claims.

I claim:

1. A clamp or hook for securing printing plates to slotted base plates provided with teeth therein, comprising a main body adapted to be dropped 75

into a slot, said main body having means adapted to engage said teeth to render the body immovable along the slot, locking means for securing said main body against upward movement, a carriage slidably mounted on said main body, and a clamping plate mounted on said carriage and adapted to engage a printing plate in securing relation.

2. A clamp or hook for securing printing plates to slotted base plates having inwardly directed teeth, comprising a main body adapted to be dropped into a slot, teeth on said main body engaging first said teeth to prevent longitudinal movement of the body in the slot, latching means for securing said main body in a slot against vertical movement, a carriage slidably mounted on the main body, and a clamping member on said carriage.

3. A clamp or hook for securing printing plates to slotted base plates having inwardly directed teeth, comprising a main body adapted to be dropped into a slot, teeth on said main body engaging first said teeth to prevent longitudinal

movement of the body in the slot, latching means for securing said main body in a slot against vertical movement, a carriage slidably mounted on the main body, a non-reversible drive for effecting movement of the carriage relative to the main body, and a clamping member on the carriage. 5

4. A clamp or hook for securing printing plates to slotted base plates, comprising a main body, a carriage slidably mounted on the main body, a clamping member on said carriage, and means 10 mounted on the sliding carriage for securing the clamp in the slot.

5. A clamp or hook for securing printing plates to slotted base plates having teeth in the slots, comprising a main body provided with teeth 15 adapted to engage said teeth, latch means securing the clamp to the base plate, a carriage slidably mounted on the main body, a non-reversible drive for effecting movement of the carriage relative to the main body, and a clamping member on 20 the carriage.

ALBERT J. HOERTH.
